WALL RACK FOR HOLDING HOUSEHOLD ARTICLES

Dorothee M. Maurer, Hafisburger Platz 2,
Munich, Germany

Filed Apr. 22, 1970, Ser. No. 22,566

Claims priority, application Germany Oct. 30, 1969

Term of patent 14 years

Int. Cl. D6—04

U.S. Cl. D33—3

FIG. 1.

FIG.2.

FIG.3.

FIG.4.

FIG.5.

FIG. 6.

FIG. 1 is a front elevational view of a wall console for holding articles, showing my new design;

FIG. 2 is a top elevational view of the wall console of FIG. 1;

FIG. 3 is a side elevational view of the console as seen from the left in FIG. 1;

FIG. 4 is a side elevational view of the console as seen from the right in FIG. 1;

FIG. 5 is a bottom elevational view of the console of FIG. 1; and

FIG. 6 is a perspective view of the console.

I claim:

The ornamental design for a wall rack for holding household articles, as shown.
